(57) **CLAIM**

We claim, the ornamental design for an applicator for implantable drug delivery, as shown and described.

DESCRIPTION

FIG. 1 is a perspective view of an applicator for implantable drug delivery, showing our new design;

FIG. 2 is a left side view of the applicator of FIG. 1;

FIG. 3 is a right side view of the applicator of FIG. 1;

FIG. 4 is top view of the applicator of FIG. 1;

FIG. 5 is bottom view of the applicator of FIG. 1;

FIG. 6 is a front view of the applicator of FIG. 1; and,

FIG. 7 is a rear view of the applicator of FIG. 1.

Broken lines used in the drawings show portions of the applicator for implantable drug delivery that form no part of the claimed design.
